(57) **CLAIM**

The ornamental design for a vehicle wheel hub cover, as shown and described.

DESCRIPTION

FIG. 1 is a front perspective view of the vehicle wheel hub cover;

FIG. 2 is a back perspective view thereof;

FIG. 3 is a top view thereof;

FIG. 4 is a bottom view thereof;

FIG. 5 is a left side elevational view thereof;

FIG. 6 is a right side elevational view thereof;

FIG. 7 is a front elevational view thereof;

FIG. 8 is a rear elevational view thereof;

FIG. 9 is a cross-sectional view thereof, sectioned along line 9-9 in FIG. 7; and,

FIG. 10 is a cross-sectional view thereof, sectioned along line 10-10 in FIG. 7.

The evenly spaced broken lines shown in the drawings illustrate portions of the vehicle wheel hub cover and form no part of the claimed design.

1 Claim, 7 Drawing Sheets
